UNITED STATES PATENT OFFICE

ALONZO H. ADAMS, OF WILKINSBURG, PENNSYLVANIA

VEHICLE SEAT CONSTRUCTION

1,090,112.

Specification of Letters Patent. Patented Mar. 10, 1914.

Application filed June 24, 1912. Serial No. 705,527.

To all whom it may concern:

Be it known that I, ALONZO H. ADAMS, a citizen of the United States, resident of Wilkinsburg, in the county of Allegheny and State of Pennsylvania, have invented 5 a new and useful Improvement in Vehicle Seat Construction; and I do hereby declare the following to be a full, clear, and exact description thereof.

10 My invention relates to vehicle-seats.

The object of my invention is to provide a seat-structure formed of metal members so riveted or secured together in connection with the metal body of the vehicle to form 15 a very strong, durable construction, which will withstand the severe jolting and usage to which such vehicles are subjected in traveling over rough country roads.

To these ends my invention comprises the 20 novel features hereinafter set forth and claimed.

In the drawings, Figure 1 is a perspective view of a buggy-body showing my invention applied thereto; Fig. 2 is a partial 25 section of a buggy-body, the section being taken transversely of the seat-structure; Fig. 3 is an enlarged cross-section and Fig. 4 is a perspective view showing how the vertical struts are secured to the cross-members.

30 Referring to the drawing, the numeral 2 designates a body of a buggy or other suitable vehicle, said body being formed of sheet-metal of suitable gage and joined at 35 the corners in any suitable manner to form an oblong rigid structure. The sides of the body adjacent the seat structure flare outwardly as at 3 and said portion is provided with the inwardly extending flanges 4.

40 The struts or uprights 5 are preferably formed in the shape of channels and the web portion at the foot is bent to form the lug 6 which is riveted or otherwise secured to the angle 7 extending around the body 45 at the lower edge thereof. The upper ends of the struts 5 are riveted or otherwise secured to the transverse members 8, said transverse members 8 having the lower flanges 9 and the upper flanges 10. The 50 lower flanges are cut away as at 11 to permit the web portion of the struts 5 to be riveted to the web portion 12 of the trans-

verse members 8. The upper ends of the struts 5 are in contact with the lower face of the upper flange 10 and consequently 55 said flange 10 rests upon said struts and the shearing strain on the rivets connecting struts to said transverse members is relieved. The inwardly extending flanges 4 of the body lap over the end portions 13 of 60 the transverse members, said end portions being cut away as at 14 to form a kind of gusset-plate, and the flanges 4 are secured to the end portions 14 of the transverse members by means of rivets 15. In this 65 manner said structure is built up in a strong substantial manner, and is so bound with the sides of the vehicle as to be further stiffened and strengthened so that all liability of the sagging or skewing of the seat- 70 frame is avoided.

The bottom plate 16 is bent as shown to form the guideway 17 which receives the lower flange 9 of the transverse member 8 and an interlocking joint is thus obtained 75 between the two members which does away with riveting or other like means for securing the bottom plate in position. By having the struts 5 slightly spaced from the side portions of the vehicle as indicated in 80 Fig. 3, the liability of rattling is avoided due to vibration which usually occurs where two metal members are brought into close relation to each other.

What I claim is:

1. In a seat-structure for vehicles, the combination with a metal body, of channel shaped struts supported thereby, transverse members secured to said struts having inwardly extending flanges, the lower flanges 90 being cut away to receive said struts, the upper flanges of said transverse members resting on said struts, and inwardly extending flanges on the body-sides secured to the upper flanges of said transverse members. 95

2. In a seat-structure for vehicles, the combination with a metal body having an inwardly extending flange around the lower edge, of channel-shaped struts, lugs formed from the web members of said struts secured 100 to said inwardly extending flanges of said body, transverse members having inwardly extending flanges at the top and bottom, the lower flanges being cut away to receive said

struts, the upper flanges resting on the tops of said struts, securing devices passing through the webs of said struts and the webs of said transverse members, and inwardly extending flanges on the body-sides connected to the upper flanges of said transverse members.

In testimony whereof, I the said ALONZO H. ADAMS, have hereunto set my hand.

ALONZO H. ADAMS.
